UNITED STATES PATENT OFFICE.

ORREN P. MOSSMAN, OF ELDORA, IOWA, AND FRANK R. NIVEN, OF ROCHESTER, NEW YORK.

HORSESHOE.

Application filed March 30, 1927. Serial No. 179,630.

This invention relates to devices used in the game or sport of "horseshoe" pitching, a contest in which either actual horseshoes, or game members of generally similar form, are pitched at a stake with the object of causing the "shoe" to embrace or "ring" the stake.

The skillful player accomplishes the desired result by pitching the shoe in such a way that it strikes the ground flatwise at the point where the stake is located, the rotation of the shoe in the air being so controlled that at the moment of striking it is in a position such that the opening between its ends is directed toward the stake. The shoe then comes to rest against the stake, which is thus embraced or "ringed."

A pitch which would otherwise secure a "ringer" may be accidentally spoiled in several ways: the shoe, when starting to embrace the stake, may have turned so far that it strikes the stake at the inner side of one end, and in this case the shoe may be turned further so that its position is reversed and its momentum causes it to slide away from the stake. Again, the shoe, after fully ringing the stake, may strike the latter so forcibly as to rebound entirely away from the stake. Finally, if the pitch is a little short, so that the shoe strikes the earth in front of the stake, the shoe may be arrested, before reaching the stake by engagement of its ends or its calks with the earth or with the edge of a shoe which has previously been pitched.

The object of the present invention is to produce a pitching shoe which, while not departing substantially from the general form of a conventional horseshoe, is so modified in certain details of form that the danger of spoiled pitches from the causes just described is substantially reduced. To this end it is proposed to use certain projections at the ends of the shoe, as more fully set forth in the following description of the preferred embodiment of the invention.

In the accompanying drawings Fig. 1 is a plan view of a pitching device or shoe embodying the present invention, shown in inverted position; Fig. 2 is a side elevation of the shoe, in upright position; and Fig. 3 is a plan view of the shoe, together with the stake at which it is pitched.

The illustrated embodiment of the invention is a pitching device having, in general, the conventional form of a horseshoe, and therefore hereinafter designated as a "horse-

shoe" or "shoe," although made and used exclusively for the purpose of a game implement. It is preferably forged from steel, in the usual manner.

As shown particularly in Figs. 1 and 3, there is, at the inner surface or edge of each end of the shoe, a short abrupt inward projection 5. The function of these projections is to retain the shoe in engagement with the stake, and thus insure the ringing of the stake, under certain conditions in which a shoe of ordinary form is likely to become disengaged from the stake.

The utility of the projections 5 is illustrated in Fig. 3. While the object of the pitcher is to cause the shoe to turn, while in the air, to precisely the extent necessary to cause its open or "heel" portion to project directly toward the stake at the moment when the shoe strikes the earth directly in front of the stake, it frequently happens that the shoe turns either farther or not so far as intended. As shown in Fig. 3, for example, the shoe, having been pitched in a direction from left to right, has turned too far, so that when it slides into engagement with the stake 13 the stake strikes the inner edge of one end of the shoe near the extremity of this end. Under these conditions the shoe tends to slide in the direction in which it was pitched, while the impact against the stake tends to turn the shoe into a position the reverse of that intended, whereupon the shoe, if of ordinary form, is likely to slide beyond and out of engagement with the stake.

The function of the projection 5 is to cause the shoe, under the conditions just described, to hang upon the stake and swing around it as on a pivot, thus remaining in ringing position. This action results from the hook-like engagement of the projection and the end of the shoe with the stake, as shown in Fig. 3.

We are aware that it has previously been proposed to provide a pitching shoe with long inward projections from each end, these projections being inclined rearwardly and toward each other so as to produce a narrowing space between them, and a narrow passage or entrance between their inward extremities for the admission of the stake. In such a form, however, the projections may, under some conditions, defeat their intended purpose, and a shoe so formed departs so

widely from the conventional form of horse-shoe as not to be admissible in regular contests. The minimum width of opening in the shoe for pitching contests is fixed by a rule, as well as the maximum overall width of the shoe, and in order to secure the greatest advantages conformable with these limitations the projections 5 should be only so long as is essential to secure the hook-like pivoting relation with the stake. The stake is commonly fixed, by convention, at one inch diameter, and as will be apparent by Fig. 3, if the center of gravity of the shoe is located at a given point, as 14, it is necessary for the projection 5 to be only long enough to cause it to embrace an arc of the stake 13 which extends slightly beyond the line intersecting the center of gravity 14 and the axis of the stake. While the precise length necessary for this purpose is, of course, dependent upon the actual size of the stake and the position of the center of gravity of the shoe, it may be said in general that the projection need in no case extend more than one-half an inch from the general line of the inner edge of the shoe. Since a pitching shoe is ordinarily at least an inch wide, it may also be stated that the projection 5 need not have a length greater than one-half the width of the end of the shoe as a maximum. Any greater length than this will be unnecessary, and will be positively objectionable if it causes the opening between the ends to be unduly restricted.

When the shoe, after being pitched, strikes the earth in front of the stake, it is desirable that it slide as freely as possible in the direction of the stake, and that its movement be not arrested by striking against a shoe which has previously been pitched. On the other hand, when the shoe has moved fully into ringing position it is desirable that it be prevented from rebounding from the stake, so that this desirable position may not be lost. In pitching-shoes as ordinarily formed, the calks serve only as means to modify the balance of the shoe, or to check its sliding movements to a certain extent. In the present shoe, however, we have so modified the form of the calks that they serve to secure the desirable results just referred to.

At each end of the shoe is a calk 6. As shown in Fig. 2, this calk has a relatively abrupt face 7 in the direction of the "toe" of the shoe, and a much more inclined opposite face 8. The slight inclination in the face 7,

as shown in the drawings, is only that which is desirable for draft in the dies by which the shoe is forged; apart from this draft no inclination is necessary or desirable. The toe-calk 9 is also formed with an abrupt face 10 and a more inclined face 11.

When the shoe strikes the earth in the proper position the inclined faces 8 and 11 of the calks permit a relatively free sliding movement until the shoe has moved into ringing position. If then the shoe tends to rebound, the calks tend to dig into the earth, the abrupt faces 7 and 10 acting to check the rebounding movement.

The pivoting effect, due to the projections 5, is the more certain in its action in proportion as the center of gravity of the shoe approaches the open or "heel" extremity. In order that the center of gravity may have this desirable position without impairing the vertical balance 5 of the shoe by using an undue amount of metal in the end-calks, the shoe is gradually thickened near the end extremities, as shown in Fig. 2, thus producing elevations 12 at the top of the shoe. These elevations, to a certain extent, counterbalance the weight of the calks vertically, thus tending to bring the center of gravity into a horizontal plane lying within the body of the shoe.

Since the space between the projections 5 is made of the full width permitted by the rules of the sport, the adjacent parts of the ends of the shoe are more widely spaced than would be the case in the absence of these projections—i. e., the sides of the shoes are more nearly parallel. From this, and from the use of the projections 12, it results that the weight of the shoe is less concentrated at its longitudinal axis, and the moment of inertia about the center of gravity is increased. This gives the shoe a greater stability in flight, permitting the user to control its inclination and its rotation with greater precision.

The invention claimed is:

A pitching device of the general form of a horseshoe, provided, at the inner side of each end, with an abrupt inward projection, said projections extending directly toward each other, determining the width of the "heel" opening and being each of a length not over half the width of the end immediately adjacent the projection.
